(57) **CLAIM**

The ornamental design for a tarpon bow light figurehead as shown and described.

DESCRIPTION

FIG. 1 is an isometric view of a tarpon bow light figurehead showing my new design;

FIG. 2 is a front elevational view thereof, the tarpon bow light figurehead includes a plain and unornamented bottom, which is not shown;

FIG. 3 is a rear elevational view thereof showing my design.

FIG. 4 is a top plan view thereof; and,

FIG. 5 is a side elevational view thereof, wherein a left side is a mirror figure of right side.
